HERMANN BRANDENBURG, OF BERLIN, GERMANY, ASSIGNOR TO JOSEF GRUENBERG
AND F. A. SCHEU GESELLSCHAFT MIT BESCHRAENKTER HAFTUNG, BOTH OF BERLIN,
GERMANY

HYDRAULIC PRINTING AND IMPRESSING OR STAMPING PRESS

Application filed April 22, 1930, Serial No. 446,331, and in Germany May 6, 1929.

With hydraulic printing and impressing or stamping presses in which the working table with the work-piece thereon is lifted by means of a liquid under pressure it is known 5 to mount the pump for said liquid and the driving motor for this pump freely in the upper or in the lower part of the frame of the press. But owing to this arrangement the pump and the motor are exposed to the dust 10 present in the air and are covered with the same, and the possibility exists that parts of the liquid under pressure, generally oil, flows down into the press or upon the work-piece, for instance a stereotypic matrix, or 15 soils the floor. Besides, the pump and the motor when arranged as above stated disturb frequently the proper management of the machine, especially when they are located in the upper part of the same. 20 The object of the present invention is to obviate these drawbacks, and in order to attain the purpose in view the bottom part of the frame of the press is so designed that the pump and the motor can be housed in a closed 25 space or chamber provided in said frame part.

Another feature of the invention resides in the following: It is suited to the proper operation of the press to obviate long conduits or pipes for the liquid between the store vessel for this latter and the pump, as 30 well as between this pump and the cylinder in which the piston that is to lift the press table is moving or reciprocating, and for 35 this reason said vessel is arranged in the bottom part of the press frame in such a manner that it surrounds and encloses said cylinder whereby, at the same time, much space is saved.

40 The space available in the bottom part of the press for housing the pump and the motor for operating the pump is, of course, very restricted, and there are, therefore, means provided rendering possible that housing in such a manner that the secure and reliable operation of the machine is not in the least impaired. This is, thus, another object of the present invention, and I attain the purpose here in view by connecting the shaft of the 45 motor and the pump gearing directly with

one another by an elastic coupling, may be of known design; this connection renders it possible to house the pump and the motor in a very small space.

For the same purpose the driving shaft and 55 the pump shaft are connected with one another by a gearing having an internal toothed wheel whereby very little space is needed also for the speeding-down gearing. This gearing with its internal toothed wheel presents, besides, the further advantage that it can be used for conveying the oil present in the lower part of the pump casing to a receptacle or basin located on a higher level from which the oil is distributed onto the driving members 60 and the shaft bearings of the pump, which members receive the oil from nozzles in the form of drops. This arrangement permits to dispense with a separate lubricating device. 70

The invention is illustrated diagrammatically and by way of example on the accompanying drawings on which Figure 1 is a vertical section through a printing and impressing or stamping press designed according to this invention; Figure 2 is a separate view of the lower part of the right hand half of Fig. 1, drawn to a somewhat larger scale and also in section, the section being taken in the plane II-II of Fig. 3; and Figure 3 is a vertical section in the plane III-III of Fig. 2. 80

On the drawings, 1 denotes the bottom part of the press, 3 the top part, and 2 are short columns or standards connecting the parts 1 and 3 with one another. 4 is a cylinder in the lower part of the press, and 5 a piston which can be moved up and down in said cylinder. Upon said piston is mounted the working table 6 which is provided with lateral extensions 7. The cylinder 4 85 is surrounded with an annular space or chamber 8 formed by a jacket 9 and containing the liquid (not shown) necessary for lifting the piston 5. In the lower part of the frame, below the table extensions 7, are two chambers 1¹ and 1², of which in the first is housed a casing 10 enclosing the pump 11 which is connected with the chamber 8 by a pipe 12, and with the cylinder 4 by a pipe 13. When the liquid is forced into said cylinder the pis- 100

ton 5 and with it the members 6 and 7 are lifted.

14 (Figs. 2 and 3) is the main shaft of the pump to which is affixed the internally toothed cog-wheel 15 which meshes with a pinion 16 secured to a shaft 17 driven by an electromotor 18 also housed in the chamber 1². The shaft 19 of this motor is connected with said shaft 17 by means of an elastic coupling 20. The pump shaft 14 is a cranked shaft. The pump has three pistons 23, and there are, therefore, three cranks and three connecting rods 21 which reciprocate said pistons by the intermediary of the double-armed levers 22.

Above said cranked pump shaft is provided an oil distributing basin 24. There is on the bottom of the pump casing 10 such an amount of oil that the cog-wheel 15 dips thereinto, the oil being, therefore, carried upwards by this wheel. A scraper 25 located in the uppermost portion of the pump casing is so arranged relatively to the said cog-wheel and the basin 24 that the oil carried upwards by the said wheel is conveyed from it into said basin, the bottom of which is provided with a plurality of nozzles 26 through and from which the oil drips upon those members of the pump driving gear that must be lubricated.

I wish it to be understood that the pump may have more than three pistons. Owing to the use of a pump having preferably at least three pistons the liquid under pressure is practically uniformly conveyed so that the piston 5 and the members 6 and 7 are lifted with practically uniform speed.

In the chamber 1² of the frame of the press are housed the electric switching members 27 required for the proper actuation and operation of the motor, etc.

It will be obvious that, owing to the arrangement and combination of parts, as described and shown by way of example, the space necessitated by the dimensions of the press, including its frame and its table, in horizontal and in vertical direction, is completely utilized. The press itself and the means for actuating and operating it (comprising the pump, the electromotor, and the switching means) form a completely self-contained structure.

I claim:

1. A hydraulic press for the manufacture of stereotype matrices, comprising in combination a frame having a middle part and two side parts, the middle part of the frame forming a support, a cylinder on said support, a piston in said cylinder and a working table connected with said piston, a liquid container surrounding said cylinder, the two side parts of said frame forming chambers beneath the working table, a pump arranged in one of said chambers, pipe connection within said chamber between said pump, said

liquid container and said cylinder respectively, a driving motor coupled to said pump and also arranged in said chamber substantially as set forth.

2. A hydraulic press for the manufacture of stereotype matrices, comprising in combination, a frame having a middle part forming a support and also having two side parts, a cylinder on said support, a piston in said cylinder and a working table connected with said piston, a liquid container surrounding said cylinder, the two side parts of said frame forming chambers beneath the working table, a pump arranged in one of said chambers, pipe connection within said chamber between said pump, said liquid container and said cylinder respectively, a driving motor coupled to said pump and also arranged in said chamber, electric switching members arranged in said second chamber, and covers for closing up said chambers.

In testimony whereof I have affixed my signature.

HERMANN BRANDENBURG.
